NUT AND BOLT ASSEMBLING MACHINE

Harry H. Gray, Kansas City, Mo.

Application July 27, 1936, Serial No. 92,808

16 Claims. (Cl. 10—155)

This invention relates to nutting machines, that is machines for screwing loose bolts and nuts together preliminary to storage or shipment to jobbers, distributors or users, and my object is to produce a machine of this character which is wholly automatic and which is rapid, efficient and dependable in operation.

I have discovered that the practical difficulty encountered in producing a machine capable of performing the function above mentioned, lies in the failure to effect alinement of the threaded bolt and nut in such fashion as to insure proper initial engagement of the threads. My object, therefore, is to devise a mechanism whereby either the bolt or the nut member may be held with the axis of its threaded portion extending in a vertical plane or approximately thereto, while a rapid spinning movement or relative rotation in a vertical plane is imparted to the members as they are brought into engagement so that if the axis of the bolt is not in a vertical plane, the spinning movement, through gyroscopic action, tends to straighten up the bolt and bring its axis to a vertical position for the proper starting of the nutting operation. The result is that alinement is insured and initial threaded engagement is positive in every case where the threaded parts are not so defective as to prevent starting or initial engagement. In this application, I illustrate one type of mechanism in which the spinning movement is imparted to the bolt member while the nut is held stationary, although obviously the nut could be spun, or both members could rotate in opposite directions.

A further object of the invention is to provide a machine which will accommodate bolts of varying length without necessitating complicated adjustments of the operative parts of the machine.

With the general objects named in view and others as will hereinafter appear, the invention consists in certain novel and useful features of construction and organization of parts as herein-after described and claimed; and in order that it may be fully understood, reference is to be had to the accompanying drawings, in which:—

Figure 1 is a plan view of a machine embodying the invention.

Figure 2 is a front view of the same omitting certain cam-operated parts in the background in the interest of clearness, such omitted parts most clearly appearing in Figures 4 to 8 inclusive, and in Figure 9.

Figure 3 is a side view of the machine.

Figure 4 is a fragmentary horizontal section on the line IV—IV of Figure 5.

Figure 5 is a fragmental central vertical section on the line V—V of Figure 4.

Figure 6 is a fragmental horizontal section in a lower plane than Figure 4, but with certain parts of the latter dotted in a different position of adjustment, and the other parts broken away to disclose some of the underlying features.

Figure 7 is a fragmental horizontal section on the line VII—VII of Figure 2.

Figure 8 is an enlarged vertical section showing the stationary post and the parts mounted thereon.

Figure 9 is a perspective view of part of the mechanism for ejecting nuts failing proper engagement with bolts.

Figure 10 is a section on the line X—X of Figure 8.

In the said drawings, a rigid framework is disclosed as comprising a base 1, a pair of angle-bar standards 2 and 3 spaced laterally apart, and other immovable bars, braces and supports, certain of which are hereinafter identified by reference characters. It is to be understood, however, that the framework of the machine may be of any type suitable as a proper support for the operative parts.

A horizontal circular table 4 is disclosed as provided with six peripheral semi-circular recesses 5, and is mounted on a stationary cylindrical post 6, for step-by-step or intermittent rotation, each recess in turn receiving one vertically-disposed bolt as another, in a diametrically-opposite recess, attains a position vertically over a nut, these actions occurring at each pause of the table between intermittent movements thereof.

To effect the operation of the table, the following mechanism is provided: An electric motor 7 on the framework (shown only in Figure 1), is connected by a belt 8, to a belt wheel 9, on a vertical shaft 10 suitably journaled in the framework.

Said shaft also carries a smaller belt wheel 11 connected by a belt 12 to a large belt wheel 13, secured on a vertical shaft 14 suitably journaled on the framework, and said shaft 14 carries a small belt wheel 15 (Figure 7), connected by a belt 16, to a large belt wheel 17 secured on a vertical shaft 18 journaled on the framework and carrying four rotatable disks, the topmost one being disk 19. Pivoted on a wrist pin 20 of said disk is one end of a link 21, pivoted also to a pin 22 of a disk 23 mounted for oscillation on the shaft or post 6, and said disk 23 has an underlying arm 24 carrying a spring-actuated pawl 25, engaging

55

a ratchet wheel 26 secured to the table 4 by a sleeve 27, the ratchet wheel teeth corresponding in number to the recesses of the table so that with each complete circle described by wrist pin 20 5 around the axis of shaft 18, the disk 23 and pawl 25 will advance far enough to turn the ratchet wheel and table one step and then withdraw to their original positions where the pawl engages the next tooth of the ratchet wheel, in readiness 10 to repeat such actions upon the ensuing revolution of shaft 18. Back rotation of the table is prevented by a spring detent 27a secured to an arm of a table-supporting collar 27b on post 6, the detent engaging a ratchet toothed hub portion of 15 the table.

A guideway disposed in radial relation to the table 4, and each peripheral recess thereof as they successively pause in radial alinement with the guideway, comprises a pair of spaced parallel rails 28 and 29 secured in fixed relation by inverted yokes 30, and the latter are secured to a bar 31 secured to the upper end of a standard 32 fastened to base 1 and to a diagonal brace 33 fastened to said standard. The rail 29 has an opening or 25 gateway 34 and an inclined bolt-carrying and feeding conduit 35, being fixed with relation to the framework and said guideway having an arcuate lower end communicating with the opening or gateway 34, the said conduit and guideway being narrower than the bolt heads but wider than the bolt stems so that the heads of the bolts B ride on the sides or rails under a guard rail 36 supported from the guideway by brackets 37, and the stems of the bolts extend downwardly between the 30 rails, the arrangement being such that by force of gravity or by other pressure, the bolts successively slide from the conduit into the guideway with their stems in the path of a slide push-bar 38 reciprocating in the guideway, the push-bar 40 having a raised head 39, which, when the push-bar is in retracted position, overhangs the guideway at the gate opening and the head of the bolt which at that time enters the guideway from the conduit, and thus guards against possible upward 45 jolting of such bolt as it is arrested by abutment against the front rail 28 of the guideway.

To effect advancement of the push-bar toward the table and its withdrawal for the admission of another bolt from the conduit to the guideway, a 50 horizontally-disposed yoke 40 is fastened to the outer end of the push-bar, and pivoted at its outer end to the yoke is a bar 41 having an upstanding inner ear 42 and an ear 43. A spring-retracted rod 44 is slidingly mounted in said ears and has 55 a downturned end pivoted to a crank 45 of a short vertical shaft 46 journaled in the framework and equipped at its lower end with an arm 47 pivotally connected by a link 48 to a rock-lever 49 on the framework, the free or inner end of the lever carrying an anti-friction roller 50 adapted to be engaged by a cam 51 depending from a second disk 51a on shaft 18.

A retractile spring 52 connected at one end to a fixed point of the framework and at the other to 60 apply a rearward pull on the rear end of the link 48 and outer end of the lever 49, tends to hold the anti-frictional roller continuously in contact with and in the path of rotary travel of the cam 51, so that the latter once in each half revolution shall 65 rock the lever and effect advance of the push-bar and thereby cause the bolt in the guideway to enter the table recess 5—at that time in alinement with the push-bar. Immediately thereafter the disk 19 completes a half-revolution and 70 the cam 51 permits the retractile spring to re-

verse the operation of the rock lever and withdraw the push-bar to its initial position and permit another bolt to enter the guideway through the gateway thereof, and during this operation, the link 21, through the second half of the rotation of the continuously revolving disk 19, causes the disk 23, through the pawl 25, to turn the ratchet wheel 26, and hence the table, one step to carry the bolt in said recess of the table a corresponding distance, and bring the next recess 5 10 into register with the guideway. As the revolution of the disk 19 ends and it begins another revolution, the link 21 rocks the pawl-carrying disk 23 back to its initial position. All the following operations of the table and bolt push-bar and 15 associated mechanism are repetitions of those described, and eventually, the first bolt suspended through the table, and retained in the recess by an arcuate plate guard 53 around the rear half of the table, is brought to a position vertically 20 over a nut to be secured upon its lower end during the pause which occurs in the operation of the table as another bolt is fed into one of the recesses 5.

Referring now to the mechanism for holding 25 and feeding nuts, one at a time, to position for engagement with a bolt, there will be noticed a nut guideway shown in alinement with, but at the opposite side of the table from the bolt guideway. The nut guideway comprises a bottom 30 plate 54, a front wall 55 and a rear wall 56, there being a gateway 57 in the rear wall 56, registering with the discharge end of a nut-holding and feeding conduit, hereinafter described.

The bottom plate 54 of said guideway fits 35 around a non-rotatable threaded sleeve 58 vertically-adjustable upon post 6, and between and in contact with an underlying disk 59 secured on the threaded sleeve 58, and a depending hub 60 of a plate 61 which serves to support the bolts 40 as they each are successively fed by push-bar 38 into the registering recess 5 of the table and until such bolts are carried around by the table and successively attain positions vertically over the inner end of the nut guide-way, the plate, 45 at such point having an open slot 62 to permit each bolt, supported with its head spaced from and above the table, to drop down onto a nut at that time occupying the said inner end of the nut guideway ready to be screwed into such nut 50 by means hereinafter described, in the interim between table operations or steps. The ensuing table step carries the nut-equipped bolt forward, the nut dragging along a fixed cam bar 63 secured to plate 61, until the said bolt is dislodged from the table to fall into a chute, not shown, for conducting the nutted bolts to a suitable receptacle, not shown. A bolt which has failed to receive a nut will not be discharged from the rotary table by the cam bar 63 (Figure 4), 60 but will be discharged by cam bar 63a (Figures 1, 2, 3 and 4), overlying rotatable table 4 in position to contact and intercept the travel of the bolt heads in the recesses 5 of said table.

The nut guideway is equipped upon its bottom 65 54 under a retaining guide 64, with a reciprocating push-bar 65, which when retracted, is outward of the gateway opening of wall 56 to permit a nut to enter the guideway from the chute or conduit 66, in rigid relation at its 70 lower or discharge end, to the bottom of the guideway, the chute or conduit being of channel type and comprising a downwardly and forwardly inclined portion and a bottom portion of arcuate form. The front end of the latter, as 75

stated, communicates with the gateway for the delivery of a nut into the latter upon each withdrawal or retraction of push-bar 65, and prior to the ensuing advance movement thereof, the 5 advance movement forcing the nut along the guideway until it reaches a stop 67, rising from the bottom 54, at which time the nut has attained a position, previously mentioned, vertically below the bolt disposed above it about the 10 same time, by the last-made step of the table.

To effect the reciprocatory operation of the push-bar 65, a rock lever 68 is mounted on a part 69 of the framework, and operated by a rotary cam 70 depending from a third disk 70a rigid on shaft 18, the lever 68 at one end carrying an anti-friction roller 71 for engagement with the cam. The other end of the lever is pivotally connected by a link 72 with a crank arm 73 of the vertical post 74 which is suitably supported for rocking movement, and the latter also has a second crank-arm 75 pivotally connected by a link 76 with the outer end of the push-bar 65. After each operation of the cam effecting inward or nut feeding movement of the push-bar 65, the roller 71 rides off the cam 70 and a push spring 77 compressed or tensioned by the operation described, reacts and effects the retraction of the push-bar and the return of the roller to the path of the cam for operation there- 20 by on the next revolution thereof.

To effect engagement between the bolt and nut, positioned as explained, in superposed relation, a clutch-operating mechanism is provided for downward movement to engage the head of the bolt for spinning action to screw it into the nut, but for first making sure that the bolt is in line for threaded engagement as pointed out in the object of the invention and as hereinafter described. The construction for accomplishing this result is disclosed, as follows: 78 is a shaft slidingly and rotatably mounted in a part of the framework and slidingly journaled thereon is a continuously rotating belt-wheel 79 driven by a belt 80 leading from a pulley 81 on the shaft 10. At its lower end the shaft 78 has a clutch 82 provided with four depending prongs, one or another of said prongs, on downward movement of the clutch, initially striking and consequently spinning the bolt head which causes the bolt to immediately come to a vertical position if not already occupying such position, and before the bolt head is received between the remaining prongs of the clutch. This bolt spinning takes place as the bolt attains a position over a nut in the nut-guideway. At an intermediate point, a part 83 of the framework carries a short threaded sleeve 84 in which the shaft 78 finds a sliding journaled support, and said sleeve is held immovable by nuts 85 on the sleeve and engaging opposite faces of the same framework part 83. Rotatable with the shaft and slidably thereon is a sleeve 86. To limit the up and down sliding movement of the sleeve, it has a longitudinal slot 86a engaging a cross-pin 86b of the shaft. The sleeve is equipped with a notched disk or clutch 87 for engagement with clutch pins 88 rotatable with pulley 79. A spring 89 bears upon the sleeve and an overlying collar 90 fixed on the shaft, and tends to hold the clutch 87 yieldingly depressed, the pin 86b limiting the downward movement by contact with the upper end of the slot. Near its upper end, the shaft finds a second bearing in the framework at 91, and at its upper end turns in a head 92 to which is pivoted the lower end of a yoke 93 pivoted at 75 its upper end to the front end of a rock lever 94

fulcrumed at an intermediate point of its length on the framework at 95, and the rear end of the lever has a pivotally pendent rod 96 connected to an upright link 97 pivotally connected to a rock-lever 98 on the framework, a spring 99 connecting the arm and framework and tending to hold the shaft 78 in elevated position, and an anti-friction roller 99a on the inner end of rock lever 98, pressed against and into the path of rotation of a cam-track 99b depending from disk 10 99c of shaft 18, the engagement and operation of the roller by cam track 99b, lowering the said shaft, and the release of the roller permitting the spring 99 to reelevate the shaft. To avoid premature checking of the lowering movement of the 15 shaft, the connection between rod 96 and link 98 is cushioned by a compression spring 100 which, however, is unyielding unless the downward adjustment of shaft 78 is arrested before the bolt has been screwed by clutch 82 into a nut. 20

As each bolt from its point of reception by the table until it attains a position over a nut in the nut guideway, rests on the plate 61 with its head spaced above the table a distance slightly exceeding the depth of the bolt head, it is apparent that 25 vertical adjustment of the plate 61 is necessary in order to accommodate the machine for operation with sets of bolts of different length, as the nut bottom plate 54 of the guideway is in fixed relation to the plate 61, disk 59 and threaded sleeve 58. 30

As one simple method of effecting such adjustment the disk 59 and said plate 61, are threaded on worm sleeve 58, which is splined for sliding but is non-rotatable on the post 6 within a fixed sleeve 104 upon the base. Said sleeve 104 is provided with a yoke 105, and within the yoke is mounted a worm wheel 106 threaded upon the worm sleeve 58. Engaging the worm wheel is a suitably journaled worm 107 operable by a hand wheel 108, the arrangement being such that rotation of the hand wheel in one direction or the other effects proper rotation of the worm wheel, which, therefore, as it is incapable of up or down movement, effects such movement of the worm sleeve and hence corresponding movement of the 45 nut bottom plate 54, the bolt abutment plate 61, and the guideway and nut chute so that bolts of any length within the capacity of adjustment provided, may be accommodated. This adjustment may also be used to control the distance the bolts 50 are screwed into the nuts. To cooperate as a guide in the vertical adjustment mentioned, an arm 66a projects from chute 66 and is fastened to a sleeve 66b fitting telescopically on standard 3. 55

As bolts usually are produced with a small fin 109 at the junction of the bottom of the head and stem, the recesses 5 in the table have upstanding semi-circular ribs 110 concentric with and of slightly greater internal diameter than the diameter of the recesses. This provides a rabbet 60 which receives such fin and usually avoids any chance of tilting of a bolt when released by clutch 82 and left wholly suspended by its head from the table, or when the clutch 82 follows it down to the point that the bolt stem is screwed 65 the full distance provided for, into the nut. However, slight irregularities in the bolt head sometimes occur which prevent the vertical alinement of the bolt above mentioned.

Sometimes a bolt or nut is defective as regards 70 its threaded portion. If such condition is encountered and the bolt, moving with the table, fails to engage and consequently is not threaded into an underlying nut, means are essential to automatically force the nut off the plate 54, as 75

otherwise it would be impossible for the push-bar 65 to dispose a second nut in place since two nuts would prevent the full stroke of the push-bar and injury to the machine would result. I have, 5 therefore, provided a reciprocatory push-rod 111, which moves forward as the table makes its next step after the clutch has revolved the bolt and has then withdrawn from engagement with the latter. The push-rod 111, in its advance, pushes 10 the nut ahead until it clears the front edge of the bottom plate 54.

The push-rod is pivoted to one end of a link 112 pivoted to an arm 113 of a short vertical shaft 114 journaled in the framework. The shaft carries a lever 115 at its upper end, and the said lever is connected by a link 116 to a forwardly-projecting arm of a slide bar 117 mounted in keepers 118 fastened to a cross-bar 119 of the framework, the slide rod also having an upstanding arm 120 for engagement by an arm 121 projecting from the hub of the disk 19 on shaft 18. A spring 123 connecting the rear end of the push-rod with the framework, is tensioned by movement to the left imparted to the slide rod by the 25 arm 121 of the hub of disk 19, and in reacting returns the push-rod 111 and slide bar 117 to their initial positions.

Operation

30 Assuming that the parts are positioned as indicated in Figures 1 and 5, where the bolt-push bar 38 is advanced and has disposed a bolt B in a recess 5 of the table and the nut push-bar is likewise advanced and holding a nut against the stop 35 67, it will be seen that as wrist pin 20 passes a dead center position to a position rearward thereof, it rocks disk 23 backward to impart similar movement to the pawl 25 until, as a half revolution of disk 19 is completed, the pawl reengages 40 the next tooth of the ratchet wheel 26. During this operation the shaft 78 descends and clutch 82 rotates rapidly and is then reelevated by reelevation of the shaft. As at this time there is no 45 bolt in recess 5 overlying the nut guideway, the operation of the clutch effects no result, but as the next operation of the pawl takes place by the second half revolution of disk 19, and thereby advances the table a one-sixth revolution in the device as illustrated, the push-rod 111 advances 50 and forces the nut forward out of the nut guideway and off the front edge of the plate 54, this action being effected by the rotary arm 121 pushing the pin 120 of the slide-bar 117 to the left (Figure 4) and thereby causing rocking of shaft 55 114, the latter through its arm 113 and the link 112 advancing the push-rod 111. As the arm 121 clears the pin 120, the spring 123, tensioned by the advance of the slide-rod or push-rod 111, reacts and returns the latter and the connected parts 60 mentioned, to their original positions, as shown by Figure 4.

Just after the second half revolution of disk 19 starts and the table has moved the bolt out of alignment with the bolt push-bar 38 and against 65 the inner edge of the concentric guide plate 53, the cam 51 starts the withdrawal movement of said push-bar, through the rock lever 49, shaft 46 and plate 41 and their connections, as shown by Figures 1 and 4. As the roller on rock-lever 70 49 is shown as engaging the periphery of cam 51, the spring 52 is employed to insure constant engagement between said parts and reverse travel of the push-bar. After the push bar has passed the gateway 34 in its reverse travel, a second bolt 75

advances from conduit 35 through the gateway and into the guideway.

The withdrawal action of push-bar 38 ends as the next recess 5 becomes aligned therewith as the second intermittent movement of the table ends, 5 and during this second table movement and withdrawal action of the bolt push-bar, the nut push-bar 65 readvances and pushes a second nut—which entered the nut guideway from chute 66 upon the completion of the withdrawal of the 10 push-bar 65—against the stop 67, and in front of slide rod 111, the operations of the push-bar 65 being effected by the action of rotary cam 70 of shaft 18, on the rock-lever 68, which lever through shaft 74 and its arms 73 and 75, and 15 link 76, effects the advance movement of push-bar 65, the spring 77, as the roller 71 clears the rear end of cam 70, reacting to return the push bar to its withdrawn position. While the push-bar 65 is advanced and the push-bar 38 has started its advance, the table is stationary, cam 99b has operated rock lever 98, and through the link 97, rod 96 and rock lever 94 have forced shaft 78 downwardly. As it descends, clutch 87 engages clutch pins 88 of revolving belt wheel 79, to effect rotation or spinning of shaft 78, the downward movement of the latter continuing until the clutch 82 barely clears the underlying rib 110 of the table.

Before the spinning operation ends and while 30 push bar 65 is still advanced, the push-bar 38 completes its advance, and push-bar 65 has withdrawn to admit another nut to the nut guideway, and by this time, the cam 99b has released lever 98 and spring 99 by pulling down on the rear 35 end of said lever and effected reelevation of the spinning shaft, and has permitted the pin 86b to strike the upper end of slot 86a of sleeve 86, and lift the clutch 87 out of engagement with pins 88, it being noted that as the shaft was forced downwardly, the first result was to engage said clutch with said pins 88 to start the spinning action, and that the continued downward movement of the shaft, overcame the resistance offered by the spring 89, so that the latter, when the cam released the lever 98, first assisted in reelevating the shaft 78 and through said pin 86b and sleeve 86, effected withdrawal of clutch 87 from clutch pins 88.

With the table provided with six recesses 5, it 50 will be apparent that the bolt appearing (Figure 1) in the recess communicating with the bolt guideway, will be stepped forward three times to reach a position over a nut in the nut guideway, and that as it attains said position, it clears or leaves the supporting plate 61 and drops through the open slot thereof and onto said nut, so that it is free to be screwed downwardly into the latter by the spinner shaft clutch pins 82 as above explained, and then be carried forwardly by the 60 next intermittent step of the table out of the open slot of plate 61, and be dislodged from the table through contact of its nut with cam bar 63. If not dislodged by the latter, or if it does not have a nut because of defective threads or the like, 65 the cam bar 63a overlying the table and carried by standard 32, will insure discharge of such bolt. As before stated, one of the prongs on the clutch 82 will invariably strike the bolt head before the head is received between the prongs and will 70 impart thereto a rapid spinning before and after it is loosely received between the prongs. Therefore, it has been found that the bolt may be slightly out of line with the nut even though the spinning shaft is axially aligned with the nut, and 75

that the effect of the spinning action is to cause the bolt to come to a vertical position in axial alinement with the bore of the nut and with the axis of the spinning shaft, which alinement assures the proper initial engagement of the threads for the operation of screwing the bolt into the underlying nut.

From the above description and drawings, it will be apparent that I have produced a machine embodying the features of advantage set forth as objectives, and it is to be understood that I reserve the right to all changes within the spirit of the invention and without the ambit of the prior art.

15 I claim:—

1. A method of securing threaded bolts and nut members together when their longitudinal axes may not be in full alinement, which consists in holding one of the members with the axis of its 20 threaded portion in a vertical plane, bringing the threaded portion of the second member into abutment with the corresponding portion of the first member without any telescopic relation between the members and while holding said second member loosely to permit of change of position of its axis without change of position of the holding means, and finally in imparting relative rotation to the members in such direction as to 25 thread the two members together.

30 2. A method of securing threaded bolt and nut members together when their longitudinal axes may not be in full alinement, which consists in holding one of the members with the axis of its threaded portion in substantially a vertical plane, 35 bringing the threaded portion of the second member into abutment with the corresponding portion of the first member without any telescopic relation between the members and while holding said second member loosely to permit change of 40 position of its axis, and then rapidly spinning one of the members in proper direction to secure initial starting of threaded engagement, and finally continuing said rotation concurrently with the application of pressure on the rotating member in the direction of its threading movement.

45 3. The method of securing bolts and nuts together which consists in placing a nut with its threaded opening extending in substantially a vertical plane and holding said nut against rotation, dropping the threaded end of a bolt into the threaded nut opening, and finally in spinning the bolt while loosely engaging same to permit it to aline itself with the threaded nut opening and enter the same.

50 4. The method of securing bolts and nuts together which consists in placing a nut with its threaded opening extending in substantially a vertical plane and holding said nut against rotation, permitting a bolt to fall under its own weight and rest substantially upright with its threaded portion in relative axial alinement with the threaded opening of the nut, and finally in imparting spinning movement to the bolt to engage 55 its threads with the nut threads.

55 5. A rotary circular table having uniformly spaced peripheral recesses, means for feeding upright bolts laterally to dispose their stems within said recesses successively, means for holding said 60 bolts with their heads spaced above the rotary table for a part of the revolution of the latter and for releasing the bolts to permit them to drop downwardly at a predetermined point, and means to feed nuts successively sidewise to a position 65 where their bores are in line to receive the re-

leased bolts to effect engagement between the bolts and nuts.

6. A rotary circular table having uniformly spaced peripheral recesses, means for feeding upright bolts laterally to dispose their stems within said recesses successively, means for holding said bolts with their heads spaced above the rotary table for a part of the revolution of the latter, means to feed nuts successively sidewise to a position where their bores are in line with the bolts to effect engagement between the bolts and nuts, and means to screw the bolts into the nuts when the table is at rest.

7. A rotary circular table having uniformly spaced peripheral recesses, means for feeding upright bolts laterally to dispose their stems within said recesses successively, means for holding said bolts with their heads spaced above the rotary table for a part of the revolution of the latter, means to feed nuts successively sidewise to a position with their bores in line with the bolts to effect engagement between the bolts and nuts, means to screw the bolts into the nuts when the table is at rest, and means to disengage the last-named means from the bolts to permit the table on its 25 ensuing step, to carry the nut-equipped bolt to ejection point of the machine.

8. A rotary circular table having uniformly spaced peripheral recesses, means for feeding upright bolts laterally to dispose their stems within said recesses successively, means for holding said bolts with their heads spaced above the rotary table for a part of the revolution of the latter and for releasing the bolts to permit them to drop downwardly at a predetermined point, means to 30 feed nuts successively sidewise to a position where their bores are in line to receive the released bolts to effect engagement between the bolts and nuts, means to impart relative rotation to the bolts and nuts to thread them together, and means to dislodge the nutted bolt from the engaged recess of the table during movement of the latter.

9. In a nutting machine, a bolt guideway, a nut guideway, an intermittently rotatable circular table having bolt-receiving peripheral recesses, means for turning the table one step to simultaneously dispose a bolt occupying one of the table recesses in line with the bore of a nut in the nut guideway and another table recess in position to receive a bolt from the bolt guideway, 45 means for retaining each bolt in its recess until after it is stationed in line with the bore of a nut in the nut guideway, means holding the bolt with the lower end of its stem and the lower face of its head in planes above that of the nut and table respectively, and for releasing each bolt when it is axially alined with the bore of a nut in the guideway, to permit such bolt to drop down upon the said nut.

10. In a nutting machine, a bolt guideway, a nut guideway, an intermittently rotatable circular table having bolt-receiving peripheral recesses, means for turning the table one step to simultaneously dispose a bolt occupying one of the table recesses in line with the bore of a nut in the nut guideway and another table recess in position to receive a bolt from the bolt guideway, means for retaining each bolt in its recess until after it is stationed in line with the bore of a nut in the nut guideway, means holding the bolt with the lower end of its stem and the lower face of its head in planes above that of the nut and table respectively, and for releasing each bolt when it is axially alined with the bore of a nut in the guideway, to permit such bolt to drop down upon 70 75

the said nut, and means for turning the bolt to screw it into the nut in the interim between table turning operations.

11. A rotary circular table having uniformly spaced peripheral recesses, means for feeding upright bolts laterally to dispose their stems within said recesses successively, means for holding said bolts with their heads spaced above the rotary table for a part of the revolution of the latter, means to feed nuts successively sidewise to a position where their bores are in line with the bolts to effect engagement between the bolts and nuts, means to impart relative rotation to the bolts and nuts to thread them together, means for discharging the connected bolt and nut from the machine during the ensuing step of the table, and means to dislodge an unnuited bolt upon continued movement of the rotary table.

12. In a nutting machine, a bolt guideway, a nut guideway, an intermittently rotatable circular table having bolt-receiving peripheral recesses, means for turning the table one step to simultaneously dispose a bolt occupying one of the table recesses in line with the bore of a nut in the nut guideway and another table recess in position to receive a bolt from the bolt guideway, means for retaining each bolt in its recess until after it is stationed in line with the bore of a nut in the nut guideway, means holding the bolt with the lower end of its stem and the lower face of its head in planes above that of the nut and table respectively, and for releasing each bolt when it is axially alined with the bore of a nut in the guideway, to permit such bolt to drop down upon the said nut, and means in the path of movement of the bolt head to effect the ejection thereof in the event the bolt fails to fall out of a recess.

13. In a nutting machine, a guideway for successively receiving nuts in upright position and reciprocatory means for periodically advancing each nut as it enters the guideway to a predetermined point, and for closing the guideway to the entrance therein of a second nut, and means for advancing at regular intervals to effect dislodgement of the nut from the machine in the event it is not otherwise dislodged.

14. In a nutting machine, a guideway for successively receiving nuts in upright position and reciprocatory means for periodically advancing each nut as it enters the guideway to a prede-

termined point, and for closing the guideway to the entrance therein of a second nut, means for advancing at regular intervals to effect dislodgement of the nut from the machine in the event it is not otherwise dislodged, and means to restore the last-named means to its initial position to avoid interference with the next nut entering the guideway upon withdrawal movement of the reciprocatory means, and disposed at the said predetermined point by following advance 10 movement of the reciprocatory means.

15. In a nutting machine, a bolt-receiving guideway having a side gateway, a bolt-carrying chute communicating with the gateway, a reciprocatory push-bar, an intermittently rotatable 15 table having equi-spaced peripheral recesses to be successively disposed in register with the discharge end of the guideway and to receive therefrom an upright bolt advanced by the push-bar, means to retain the bolt within the recess in the 20 ensuing rotatable step of the table, and a plate underlying said bolt and supporting the same, with its head spaced from the top of the table until the latter in its rotation disposes the bolt at a predetermined point, means for holding a nut 25 stationary in a plane below that of said plate and with its bore for engagement by said bolt when released from said plate.

16. In a nutting machine, a bolt-receiving guideway having a side gateway, a bolt-carrying 30 chute communicating with the gateway, a reciprocatory push-bar, an intermittently rotatable table having equi-spaced peripheral recesses to be successively disposed in register with the discharge end of the guideway and to receive there- 35 from an upright bolt advanced by the push-bar, means to retain the bolt within the recess in the ensuing rotatable step of the table, and a plate underlying said bolt and supporting the same, with its head spaced from the top of the table 40 until the latter in its rotation disposes the bolt at a predetermined point, means for holding a nut stationary in a plane below that of said plate and with its bore for engagement by said bolt when released from said plate, a rotary clutch, 45 and means to reciprocate the clutch into engagement with the bolt for screwing the same into the nut, and out of engagement with the bolt, in the interim between table operations.
